UNITED STATES PATENT OFFICE.

ANGUS M. LANDER, OF PELZER, SOUTH CAROLINA.

BALE-TIE.

SPECIFICATION forming part of Letters Patent No. 718,133, dated January 13, 1903.

Application filed May 3, 1902. Serial No. 105,820. (No model.)

To all whom it may concern:

Be it known that I, ANGUS M. LANDER, a citizen of the United States, residing at Pelzer, in the county of Anderson and State of 5 South Carolina, have invented certain new and useful Improvements in Bale-Ties; and I do hereby declare the following to be a full, clear, and exact description of the invention, such as will enable others skilled in the art 10 to which it appertains to make and use the same.

This invention relates to bale-ties, having reference to the construction of the band which surrounds the bale and the fastening 15 device by means of which the extremities of the band are coupled and held together.

The object of the invention is to provide a simple, cheap, and effective means for fastening together the ends of a thin flat metallic band, the band being provided with 20 terminal loops, which are formed at the ends of the band before applying the fastening device. The terminal loops are so formed that when tension is put upon the band the loops 25 are rendered self-binding with respect to the fastening device, thereby rendering it impossible for the loops to straighten out and release themselves from their engagement with the fastening device.

30 With the above and other objects in view, the nature of which will more fully appear as the description proceeds, the invention consists in the novel construction, combination, and arrangement of parts, as hereinafter fully 35 described, illustrated, and claimed.

In the accompanying drawings, Figure 1 is a perspective view showing the bale-tie applied to a bale. Fig. 2 is an enlarged perspective view of a portion of the band, showing 40 the fastening device in engagement therewith. Fig. 3 is an enlarged sectional view through the permanent loops, showing the relationship existing between the loops and the arms or fingers of the fastening device.

45 Referring to the drawings, 1 designates a band or strap of thin flat metal, such as is commonly known to the trade as "hoop-iron." The band may be quite thin, approximately of the thickness of card or bristol 50 board, and each end of the band is bent to form a flat elongated loop 2, one of the important features of which resides in continu-

ing the formation of the loop far enough to provide two thicknesses at the inner portion of the loop or at the point 3, where the loop 55 binds against the inner edge of one of the fingers of the fastener, the extreme end portion of the band being extended part way toward the outer portion of the loop, so that in reality the band completely encircles or passes 60 around the inner edge of one of the fingers or arms of the fastening device twice.

The fastening device by means of which the ends of the band are coupled together consists of a flat plate 4, having a slot or notch 65 5, which serves to provide the plate or fastening device with two arms or fingers 6 of a size adapting them to be inserted in the loops of the band. After the band has been passed around the bundle or bale and the fingers of 70 the fastening device have been inserted in the loops the outward pressure of the material of the bale and the tension produced thereby on the band will tend to draw apart the looped extremities of the band, thus forcing 75 the same into firm engagement with the inner edges of the fingers 6. Owing to the fact that the material of the band passes twice around the inner edge of each finger of the fastening device, the loop is rendered self 80 tightening or binding, the outer portion or thickness of the loop acting against the inner portion or thickness of the loop at the point 3 to compress the loop and bind the same closely upon and around the finger or arm 3, 85 which is inserted through the loop. Slipping or displacement of the loop from the fastening device is thus rendered impossible, and the ends of the band will be securely held until the band is taken off. 90

The bale-tie hereinabove described is economical in construction both as regards the fastening device and the band, as but little material is consumed in the formation of the terminal loops, while the fastening device 95 may be either cast or stamped out of sheet-metal without waste. The device also enables the bale to be compactly held together and the original size thereof maintained, as there can be no slipping of the band. The bale-tie may be applied with great rapidity, it only being necessary to pass the band around the bale and place the arms or fingers of the fastener through the terminal loops. The bands 100

may all be of equal length, thus giving uniformity in the size of the bales or bundles and equal tension on all the bands.

Having thus described the invention, what is claimed as new is—

5 In a bale-tie, the combination of a thin flexible metallic band having permanently-formed terminal loops made by bending the extremities of the band upon themselves so as to provide two thicknesses at the inner adjacent portions of the loops, and a connect-

ing-fastener consisting of a flat plate having parallel fingers spaced apart and adapted to be removably inserted in the terminal loops of the band, substantially as described.

15 In testimony whereof I affix my signature in presence of two witnesses.

ANGUS M. LANDER. [L. S.]
